Primary Examiner — Katrina N Gonzalez

(57) **CLAIM**

The ornamental design for a cat litter box, as shown and described.

DESCRIPTION

FIG. 1 is a front, left and top perspective view of a cat litter box showing my new design;

FIG. 2 is rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 2; and,

FIG. 10 is another perspective view thereof, but shown in a usage state in an environmental view.

The broken lines depict portions of the cat litter box that form no part of the claimed design. The dash-dot-dash broken lines are for noting enlarged views and form no part of the claimed design.
